FIG. 1

Des. 209,024

PAGE 2

FIG. 2

FIG. 3

FIG. 4

FIG. 1 is a front perspective view of a portable adding machine or similar article showing my new design;

FIG. 2 is a rear perspective view thereof;

FIG. 3 is a left side elevational view; and

FIG. 4 is a top plan view thereof.

The broken line showing of the cover has been omitted from FIGS. 2, 3, and 4 for convenience of illustration.

The dominant features of my design reside in the full-line portions of the drawings.

I claim:

The ornamental design for a portable adding machine or similar article, as shown and described.
